UNITED STATES PATENT OFFICE.

ARTHUR F. CASE, OF CLEVELAND, OHIO, ASSIGNOR TO THE WELLMAN-SEAVER-MORGAN COMPANY, OF CLEVELAND, OHIO, A CORPORATION OF OHIO.

CAR-HAULAGE SYSTEM FOR MOVABLE CAR-DUMPERS.

1,322,538.

Specification of Letters Patent.

Patented Nov. 25, 1919.

Application filed March 19, 1919. Serial No. 283,632.

To all whom it may concern:

Be it known that I, ARTHUR F. CASE, a citizen of the United States, residing at Cleveland, in the county of Cuyahoga and State of Ohio, have invented a certain new and useful Improvement in Car-Haulage Systems for Movable Car-Dumpers, of which the following is a full, clear, and exact description.

10 This invention relates to car dumpers of the type which are movably supported on a track so that they may be moved from point to point to vary the points of discharge of material dumped from the cars.

15 In movable dumpers of this type, the dumper itself is adapted to travel along a suitable track of wide gage, spaced on both sides of the rails of a track along which are moved the cars to be dumped. The frame or 20 tower of the dumper has inclined approach and take-off tracks which extend with suitable inclination from opposite ends of the dumper down to the rails of the car track, the loaded cars being brought up one of 25 these inclined tracks, and the empty cars run down the other inclined track. As the dumper is moved along the rails of what may be termed the dumper track, the inclined tracks of the approach and take-off 30 slide over the rails of the car tracks so that wherever the dumper is positioned, the cars may be brought up onto the cradle from one end of the dumper, and the empty cars may be run down to the same track from the 35 other end of the dumper.

40 In operating a dumper of this kind, a locomotive is usually employed to position the cars one at a time, on the cradle of the dumper and to push the empty cars off the cradle, it being customary for the locomotive to push a string of loaded cars up toward the dumper, and when the foremost car is properly positioned thereon, this car is uncoupled and allowed to stand on the 45 cradle while the locomotive and the remainder of the string of loaded cars are backed away from the dumper. This operation is repeated each time a loaded car is positioned on the dumper, and as it requires a crew of men, obviously considerable expense is involved in the handling of the cars.

50 The principal object of the present invention is to provide for use in connection with a movable dumper, a car haulage system involving a haulage car such as is commonly

employed with stationary dumpers, with the parts so constructed and arranged that the haulage system is at all times available for use, irrespective of the position to which the dumper is moved along its line or range 60 of movement.

More specifically considered, the invention aims to reduce the cost of handling the cars to be dumped, and to increase the speed of operation.

65 The invention may be briefly summarized as consisting in certain novel combinations and arrangements of parts which will be described in the specification and set forth in the appended claims.

70 In the accompanying sheets of drawings wherein I have shown the preferred embodiment of my invention, Figure 1 is a view partly in elevation and partly in section, showing my improved haulage system applied to a movable dumper, this view showing only a portion of the system or trackways for the dumper and cars; Fig. 2 is a plan view of the same; Fig. 3 is a plan view looking down on the inclined approach 75 track, the same being on an enlarged scale and showing also a portion of the movable haulage car track; Fig. 4 is a sectional side elevation of the same; Fig. 5 is a similar view showing the upper part of the inclined approach and a portion of the dumper to which it is attached; Fig. 6 is a transverse sectional view showing the dumper tracks, 80 car track, and pit or trough which is between the rails of the car track and accommodates the haulage car runway or the supporting structure for the track of the haulage car, which structure is movable along the trough with the dumper; Figs. 7 and 8 are sectional views along the lines 7—7 and 8—8 respectively of Fig. 1; Fig. 9 is a sectional view substantially along the line 9—9 of Fig. 4, looking in the direction indicated by the arrows; and Fig. 10 is a sectional view substantially along the line 10—10 of 85 Fig. 4.

90 Referring now to the drawings, 10 represents conventionally a movable car dumper of usual construction having wheeled trucks 105 11 which are designed to run along the rails 12 (see particularly Fig. 6) of a so-called dumper track, so that the dumper can be positioned wherever desired along the track 12 to discharge the material from the cars at different points. The car dumper includes 110

a suitable frame or tower, and a cradle which may be tilted or first elevated and then tilted to turn the car sidewise and dump the material therefrom. Dumpers of 5 this type are so well-known that further description and detail drawings are believed to be unnecessary.

The empty and loaded cars are run on a track whose rails are shown at 13, this track 10 being on a slight inclination, preferably about 1% for some distance in advance of and throughout the length of travel of the dumper and of the parts of the haulage system associated therewith. As is clearly 15 shown in Fig. 6, the track 13 extends between the rails of the dumper track 12, the two rails of the dumper track for each side of the dumper paralleling the rails of the car track 13 for a distance depending upon 20 the distance or length of travel that the dumper is to have.

Extending downward from one end of the dumper is an inclined approach 14 for the loaded cars, and extending from the other 25 end of the dumper is an inclined take-off 15 for the empty cars, both the approach and the take-off consisting of wedge-shaped or tapered built-up structures as indicated in Figs. 4, 5 and 10, having wheels 16, which 30 run upon the rails of the car track 13 (see Figs. 4, 5 and 10), and each being connected to the end of the dumper in any suitable manner such as by links 17, one of which is shown in Fig. 5, or otherwise. The approach and take-off are provided respectively with inclined approach rails 14^a and inclined take-off rails 15^a, these rails having the same gage as the car track 13, and at their lower or free ends, *i. e.*, at the base of 40 the incline, resting on the rails of the track 13 in much the same manner that the inclined rails of the approach and take-off of the ordinary movable dumper extend from the rails of the car track up to the dumper. 45 At their upper ends these inclined rails 14^a and 15^a of the approach and take-off are in line with, and form continuations of the rails on the tower and platen of the dumper when the cradle is in normal position, or in 50 position to receive a car.

Coming now to the features directly involving my invention, I provide between the rails of the car track 13, a long pit 18, which extends a considerable distance beyond the 55 approach side of the dumper track and lengthwise of the latter, substantially to, and if desired, beyond the opposite end of the dumper track. At the bottom of this pit are the rails 19 of a narrow gage track, 60 on which travels what may be termed a movable haulage car runway 20 composed of a series of units 20^a, 20^b, 20^c and 20^d which are connected together as by means of links 21, (see particularly the left hand end of 65 Fig. 4) these runway units being in the

form of carriages or trucks built up from structural material and provided with wheels 22 which run on the rails of the track 19 at the bottom of the pit. It might be here stated that the rails of the track 19 are parallel to, and a uniform distance 70 below the rails of the upper car track 13 (which are positioned just beyond the side walls of the pit as shown in Figs. 6, 7 and 8) except at one end of the pit there is an upwardly inclined section of the track 19 extending from the bottom of the pit upwardly to the upper surface supporting the car track 13, so that the haulage car runway 20 can be run out of the pit if desired. This 75 is illustrated in Fig. 1. This movable haulage car runway 20, composed of the connected units 20^a, 20^b, 20^c and 20^d is connected to the approach 14, so that when the car dumper is moved along the dumper tracks 80 in either direction, the approach 14, take-off 15 and haulage car runway 20 move with it. The forward section 20^c of the runway is connected to the approach (which in turn is connected to the dumper as before stated) 90 by any suitable means such as links 23, the section 20^d having its forward end, that is to say, its end toward the dumper, inclined upwardly as shown most clearly in Fig. 4, and extending inwardly for a distance 95 between the inclined rails 14^a of the approach 14.

The movable haulage car runway 20 is provided with a track 24, for a haulage car 25, or so-called mule, shown in Figs. 1, 2 100 and 8, which track 24 is like the runway track 19, a narrow gage track with a gage considerably smaller than the gage of the car track 13. The haulage car track 24 has a lower or depressed portion carried by the 105 section 20^c of the haulage car runway 20, this portion including a lower horizontal portion 24^a which is a sufficient distance below the car track 13 that when the haulage car is on this portion, a loaded car may be 110 run over the haulage car in the manner indicated in Fig. 1. From the lower horizontal portion 24^a, the haulage car track 24 inclines upwardly, as shown at 24^b, to substantially the level of the car track 13, this 115 portion, which may be designated by the reference character 24^c, being carried by the runway sections 20^b, 20^c and 20^d. On the forward runway section 20^d, next to the dumper, the haulage car track 24 inclines 120 upwardly in conformity with the inclination of the rail 14^a of the approach, this portion being designated 24^d. Beyond the forward section 20^d of the runway, the haulage car track is continued up the approach to 125 the dumper by a section 24^e, this latter section being carried by the approach. It might be mentioned that there are joints in the haulage car track where the joints occur 130 in the runway, *i. e.* between the sections 20^a, 20^b, 20^c and 20^d.

and 20^b, 20^b and 20^c, 20^c and 20^d, and between the section 20^d and the approach, so that sufficient flexibility is afforded to allow the various sections of the runway to conform to any slight irregularities which may exist in the track upon which the runway travels.

The haulage car 25 may be similar in construction to the haulage cars frequently utilized with stationary dumpers, and it may be operated in much the same fashion as the latter, the prime difference between the old construction and the present construction being that with the stationary dumpers the haulage car travels on a wholly stationary track, whereas in my improved construction constituting the subject matter of this invention, the haulage car travels over the track of a movably runway which may be moved with the dumper. Preferably the haulage car is moved toward the dumper by a haulage rope 26, and is pulled back to the far end of the runway, *i. e.* to the lower or depressed portion of the runway by a tail rope 27. The haulage rope passes over a series of sheaves 28 suitably positioned near the top of the runway, and the tail rope around suitable sheaves 29 near the bottom of the runway, and at the dumper they pass around customary drums (carried by the dumper) which need not be shown as their operation is well understood by those skilled in the dumper art. At the lower end of the section 24^a of the runway, a suitable stop or abutment 30 is provided, which will include spring bumpers to stop the movement of the haulage car in the direction away from the dumper.

In operation, when the haulage car is down at the far end of the runway, *i. e.* in the pit, as indicated in Fig. 1, a loaded car is allowed to drift down the slight incline of the car track 13, and it will come to a stop when it reaches the approach track 45 14^a, that is to say, it will stop a short distance beyond the inclined portion 24^b of the haulage car track, so that as soon as the loaded car is thus positioned, the haulage car is pulled up out of the pit up to the rear 50 of the loaded car, and then pulls the loaded car up onto the dumper, the loaded car pushing the empty car already on the cradle of the dumper down the take-off 15. As soon as the loaded car is positioned on the 55 cradle of the dumper, the haulage car is pulled back along the runway in the far end thereof until it again occupies the position in the pit, as shown in Fig. 1. Thereupon, and while the loaded car is being 60 handled in the dumper, the next loaded car is allowed to drift down past the haulage car, and it will in turn be pulled up onto the dumper. This will be repeated as rapidly as the cars can be handled in the dumper.

65 When it is desired to change the point

of delivery of the material, the dumper will be moved along the dumper tracks 12, and when it is thus moved, the runway for the haulage car, as well as the approach 14 and take-off 15 move with the dumper without 70 in any way affecting the operation of the haulage system.

Thus it will be seen that I have effected a very important improvement in movable dumpers since I am enabled to eliminate the services of several men constituting the crew which was required heretofore to bring the loaded cars up onto the cradle of the dumper. Additionally the speed of operation can be somewhat increased over that 75 which obtains when a locomotive is used for handling the loaded cars. Still further my improved system is safer for the operators than the prior haulage system requiring the use of a locomotive.

80 I believe it is broadly new with me to provide a movable runway for the haulage car, which runway can be moved about desirably though not necessarily with the dumper. Obviously, therefore, I am not to 85 be confined to the exact arrangement and details shown, as numerous changes may be made without departing from the spirit and scope of my invention in its broad aspects.

Having described my invention, I claim: 90

1. In combination with a movable car dumper, a haulage system for moving loaded cars up onto the dumper, comprising a haulage car for shifting the loaded cars, and a movable runway for the haulage car. 100

2. In combination with a movable car dumper adapted to be moved along a track, a car track for loaded cars, a haulage system for moving the cars from said car track onto the dumper, and a movable runway for the haulage car connected to the dumper so as to move therewith. 105

3. In combination with a movable car dumper and a track along which the dumper is adapted to be moved, of a haulage system comprising a haulage car adapted to shift loaded cars onto the dumper, a movable runway having a track for the haulage car, and a stationary track on which said runway is adapted to be moved. 110

4. In combination with a movable car dumper and a track along which the dumper is adapted to be moved, of a haulage system comprising a haulage car adapted to shift loaded cars up onto the dumper, a movable runway having a track for the haulage car, and a stationary track on which said runway is adapted to be moved, said runway being connected to the dumper so as to move therewith. 120

5. In combination, a movable car dumper, a track along which said dumper is adapted to be moved, a car track for cars to be handled by the dumper extending along the track for the dumper, a haulage system for 130

- 4
- the cars comprising a haulage car for moving the cars onto the dumper, and a movable runway for the haulage car having a track for the haulage car with a portion extending downward below said car track. 5
6. In combination, a movable car dumper, a dumper track along which the dumper may be moved, a car track for cars to be handled by the dumper, said car track extending along the dumper track, a haulage system comprising a haulage car, a movable runway for the haulage car, a pit extending beneath and lengthwise of the car track, a movable runway for the haulage car, a track 10 in the pit along which said runway is adapted to be moved, said runway having a track for the haulage car located between the rails of the car track and comprising a portion extending downward beneath said car track. 15
7. In combination with a movable car dumper, a car track for loaded cars, a pit extending lengthwise of the track between the rails of the latter, a runway track at the bottom of the pit, a haulage car runway 20 movable along said runway track and connected to the dumper, said runway having a haulage car track leading to the dumper and having a portion at substantially the 25 level of the car track, and another portion extending downward below the latter. 30
8. In combination with a movable car dumper and a track along which the dumper may be moved, a car track for loaded cars, the dumper having an inclined approach supported on the car track and having inclined rails leading from the latter to one end of the dumper, a haulage system for moving the cars from the car track up the approach onto the dumper comprising a haulage car, a movable runway for the haulage car and a stationary track for said runway, said runway having rails for the haulage car located between the rails of the car track, the haulage car track at the end of the runway remote from the dumper being 40 below the level of the car track and extending therefrom up to substantially the level of the car track, said approach having between the inclined car rails referred to, inclined haulage car rails forming continuations of the haulage car rails carried by the 45 runway. 50

In testimony whereof, I hereunto affix my signature.

ARTHUR F. CASE.
